UNITED STATES PATENT OFFICE

2,332,498

SHAVER

Arthur W. Burks, Decatur, Ill., assignor to Decatur
Pump Company, Decatur, Ill., a corporation of
Illinois

Application June 14, 1940, Serial No. 340,533

6 Claims. (Cl. 30—43)

The present invention relates in general to devices for clipping hairs, especially mechanically actuated shavers, and is particularly concerned with improvements in the cooperatively associated clipping and shaving instrumentalities.

More specifically, the present invention seeks to provide an improved cutting head construction having a novel cutter blade guard, which is simple in construction, efficient in operation, and which is not apt to get out of order or give trouble over long periods of use.

A further object of the herein described invention is to provide a shaving device wherein the cutter guard and hair guiding means is mounted for free rotational movement during the shaving operation and may be rolled over the face instead of being dragged, as in the usual arrangements.

A further object is to provide a shaving device having an improved cutting blade arrangement.

Still another object of the invention is to provide an improved shaving implement of the above type, in which a plurality of blades are driven by a single motive device but are supported for independent edgewise movement under the action of centrifugal force during the shaving operation.

Other objects and features of the invention will more fully appear from the following detailed description, taken in connection with the accompanying drawing, which illustrates a preferred embodiment thereof, and in which:

Figure 1 is a side elevational view of a shaver embodying the features of the herein described invention;

Figure 2 is an enlarged view of the same, with a portion of the casing cut away at one end and showing the cutting head and adjacent portion of the casing in section; and

Figure 3 is a transverse section taken through the blade guard, the blade and associated parts of the guard being shown in full lines, taken substantially on the line III—III of Figure 2.

As shown on the drawing:

The present invention is susceptible of use in mechanical shavers and may be actuated by any suitable power source. In the present instance, the invention is illustrated as being embodied in a shaver of the electric type wherein a casing 10 is provided for enclosing the power mechanism, in this instance an electric motor. As is the usual practice, the casing may be provided at one end with a connection cord 11, by means of which the motor may be connected to a suitable source of electrical energy.

The shaver head assembly, as generally indi-

cated at 12, is mounted at the opposite end of the casing 10, this head embodying the hair-cutting instrumentalities. More specifically, the casing at the head end of the shaver is of solid construction and is formed so as to have stepped grooves 13 and 14 of progressively decreasing diameter for effecting surfaces upon which certain of the mounting parts for the head may be supported.

Disposed in the groove 13, there is an anti-friction bearing of the usual construction containing inner and outer ball races 15 and 16 which are cooperatively associated with ball bearings 17. The inner ball race 15 is retained in the groove 13 by means of a retaining ring 18 which is secured in the groove 14 as by screws 19. The peripheral margin of this retaining ring extends over and engages the uppermost edge of the inner ball race. If desired, small dowel pins 20 may be provided for interconnecting the retaining ring with the inner ball race.

Surrounding the outer ball race, there is provided a ring member 21 having a shallow groove 22 at its lowermost end portion. This groove is on the inner surface of the ring and provides a seat for the outer ball race. The upper inner portion of the ring 21 is provided with suitable teeth to form an internally toothed ratchet wheel, these teeth being shown at 23.

A cutter guard 24 of frusto-conical shape is secured to the ring 21, the cutter guard being provided with an integral peripheral flange 25 which is adapted to be disposed over the outer surface of the ring 21. This flange, ring 21, and outer ball race are secured together to form a unit by means of suitable screws 26 which are arranged to have their innermost ends set against the outer ball race.

With the arrangement just described, it will be apparent that the cutter guard will be mounted so that it may rotate freely about its axis during the shaving operation. Thus, the cutter guard may be rolled over the face during the shaving operation and will not be dragged over the skin, as in the usual arrangements. This has been found to constitute a very desirable novel construction which eliminates to a great extent chafing of the skin and other irritations which may result due to dragging the ordinary cutter guard over the skin while shaving with the ordinarily constructed cutter guards of mechanical shavers.

While in the present instance I have disclosed the cutter guard as being provided on its active surface with a plurality of perforations as shown at 27, it will be readily appreciated that these perforations may vary as to shape. That is, the

perforations may be slots, holes and the like which will receive the hairs and permit them to project through the inner surface of the guard, where they may be severed by a suitable cutter.

As clearly shown in Figure 2, the closed end of the casing may be provided with a central bore 28 which is fitted with spaced bearings 29 and 30 for supporting the adjacently disposed ends of a main driving shaft 31 and a shaft extension 32. The adjacently disposed ends of the main shaft and the shaft extension may be interconnected in the space between the bearings 29 and 30 by a flexible shaft coupling, as generally shown at 33.

The shaft extension 32 projects within the cutter guard 24 and has its axis coincident with the axis of the guard. This shaft is of bifurcated or split construction throughout a portion of its length for overlappingly receiving the innermost edges of a pair of radially extending cutter blades 35 and 36. The innermost edge of each cutter blade is provided with spaced slots 37 for respectively receiving an associated pin 38 carried by the shaft. The pin and slot arrangement enables the blades to move outwardly and inwardly in an edgewise direction under the action of centrifugal force when the shaft 32 is being rotated during the operation of the shaver.

The outermost edges of the cutter blades are angularly disposed to respectively define inclined cutting edges 39 which are adapted to engage the undersurface of the cutter guard and be slid thereover, when the shaft extension 32 is rotated.

In the shaver described herein, the extension shaft is rotated in one direction only. With the cutter guard mounted for rotation, it will be apparent that there would be a tendency for the cutter guard to follow the direction of movement of the cutter blades. In order to constrain the cutter guard against rotation in the same direction as that in which the cutter blades are moving, there is swingably mounted on the ring 18 a latching pawl 40. This pawl is pivoted at one end on a pivot screw 41 and is arranged at its free end to engage the inwardly extending teeth 23 of the annular ring 21. The pawl 40 is retained in latching position by means of a suitable spring 42 which is anchored at one end to the retaining ring 18 and has its free end bearing against the pawl.

From the foregoing description, it will be apparent that the present invention provides an improved shaver having an improved cutting head construction which utilizes a novel cutter blade guard; which is simple in construction, efficient in operation, and is not apt to get out of order or give trouble over long periods of use; which embodies a novel cutter guard and hair guiding means mounted for free rotational movement during the shaving operation so as to enable the guard to be rolled over the skin instead of being dragged, as in the usual arrangements; which utilizes an improved cutting blade arrangement; and in which an improved shaving implement is provided having a plurality of blades driven by a single motive device, but wherein the blades are supported for independent edgewise movement under the action of centrifugal force during the shaving operation.

It will, of course, be understood that various details of construction may be varied through a wide range without departing from the principles of this invention, and it is, therefore, not the

purpose to limit the patent granted hereon otherwise than necessitated by the scope and spirit of the appended claims.

I claim as my invention:

- 5 1. In a device of the character described, a cutting head having a perforate portion, a rotatable shaft, a blade carried by the shaft for rotation therewith and having a cutting edge for cooperating with said portion, means independent 10 of said shaft supporting said portion for rotation in a direction the same as or in opposition to the rotation of said blade, and means for opposing rotation of said portion in the direction of movement of said blade.
- 15 2. In a device of the character described, a cutting head having a perforate portion, a rotatable shaft, a blade carried by the shaft for rotation therewith and having a cutting edge for cooperating with said portion, means independent 20 of said shaft supporting said portion for rotation in a direction the same as or in opposition to the rotation of said blade, and ratchet means opposing rotation of said portion in one of said directions.
- 25 3. A hair cutting device comprising an elongate casing, a perforate member mounted for free rotation on one end of the casing, means for constraining the free rotation of said member in one direction only, a rotatable shaft separate 30 from said perforate member and disposed with its axis extending longitudinally within the casing and having one end adjacent the perforate member, and a cutting blade carried by and movable with the shaft, said blade having a cutting edge engageable with and movable over the undersurface of said member, said blade and member being movable in opposite directions but constrained against movement in the same direction.
- 35 4. A hair cutting device comprising a hollow housing, an anti-friction member having its inner raceway embracing an end of said housing, a perforate cup-shaped cutting head surrounding and being connected to the outer raceway of said 40 anti-friction member, a rotatable shaft within 45 and extending beyond said casing and terminating in spaced relation from said cutting head, and a cutting blade carried by said shaft for movement together with and relative to said shaft, said cutting blade having a cutting edge for cooperating with said cutting head.
- 50 5. A hair cutting device comprising an elongate hollow housing having adjacent annular recesses of different diameters at one end, an anti-friction bearing member seated within one of said recesses, means in the other of said recesses for maintaining said anti-friction member in said one recess, a cutting head having a thin frustoconical perforate portion and a cylindrical portion, said cylindrical portion being connected to said anti-friction member for free rotation therewith, a rotatable shaft in said casing extending beyond said recessed end and terminating in 55 spaced relation from the end of said frustoconical perforate portion, and a blade carried by said shaft for rotation therewith and having a cutting edge for cooperating with said perforate portion.
- 60 6. A hair cutting device comprising an elongate hollow housing having adjacent annular recesses of different diameters at one end, an anti-friction bearing having its inner raceway seated within one of said recesses, an annular ring in the 65 other of said recesses having a peripheral por-
- 70
- 75

tion seated on said inner raceway, a second annular ring embracing the periphery of the outer raceway of said anti-friction bearing and having teeth on its inner periphery above said outer raceway, a spring pressed ratchet on the first-mentioned annular ring engaging said teeth for restricting rotation of said second annular ring in one direction only, a perforate cup-shaped cutting head embracing said second annular ring for rotation therewith, a rotatable shaft in and extending beyond said one end of the casing and terminating in spaced relation from said cutting head, a slot through said shaft in its portion ex-

tending beyond said casing, spaced pins bridging said slot, a pair of blades having cutting edges along opposite margins and overlapping portions seated within said shaft slot, and registered slots in the overlapping portions of said blades for receiving said pins therethrough, said pins and slots cooperating to guide said blades in edgewise movements radially of said shaft in response to centrifugal force for seating the cutting edges thereof against the inner surface of the perforate cutting head when said shaft is rotated.

ARTHUR W. BURKS.
